FOOD PACKAGING MACHINE

Carl Byrd, Chicago, Ill., assignor to Standard Packaging Corporation, Chicago, Ill., a corporation of Virginia

Application November 10, 1954, Serial No. 33,054

Term of patent 14 years

(Cl. D55—1)

FIG. 1

Des. 176,307

PAGE 2

FIG. 2

The rear wall of the food packaging machine illustrated, not shown, is substantially plain.

I claim:

The ornamental design for a food packaging machine, substantially as shown and described.
